US00D818805S

(12) **United States Design Patent** (10) **Patent No.:** **US D818,805 S**
(45) **Date of Patent:** **** May 29, 2018**

(54) **PLATE AND HOOK**

(71) Applicant: **Home Depot Product Authority, LLC,**
Atlanta, GA (US)

(72) Inventors: **Erica Knight**, Chamblee, GA (US);
Michael Nelson, Peachtree City, GA
(US)

(73) Assignee: **Home Depot Product Authority, LLC,**
Atlanta, GA (US)

(**) Term: **15 Years**

(21) Appl. No.: **29/571,758**

(22) Filed: **Jul. 21, 2016**

Related U.S. Application Data

(62) Division of application No. 29/506,444, filed on Oct. 15, 2014, now Pat. No. Des. 763,667.

(51) **LOC (11) Cl.** **08-05**
(52) **U.S. Cl.**

USPC **D8/376**

Primary Examiner — Cynthia Underwood

(74) *Attorney, Agent, or Firm* — Greenberg Traurig, LLP

(57) **CLAIM**

The ornamental design for a plate and hook, as shown and described.

DESCRIPTION

FIG. 1 is a perspective view of first embodiment of our design;

FIG. 2 is a front view thereof;

FIG. 3 is a left side view thereof, the right side view thereof being a mirror image;

FIG. 4 is a top view thereof;

FIG. 5 is a bottom view thereof;

FIG. 6 is a perspective view of a second embodiment of our design

FIG. 7 is a front view thereof;

FIG. 8 is a left side view thereof, the right side view thereof being a mirror image;

FIG. 9 is a top view thereof; and,

FIG. 10 is a bottom view thereof.

The dashed lines in the figures represent environmental structure only and form no part of the claimed design. The stippling in FIGS. 6-10 represents a rough surface finish.

1 Claim, 8 Drawing Sheets
